UNITED STATES PATENT OFFICE.

JAMES ANSON SHARPNACK, OF RICES LANDING, PENNSYLVANIA.

FACING TOOL.

1,423,462.

Specification of Letters Patent. Patented July 18, 1922.

Application filed February 5, 1921. Serial No. 442,781.

To all whom it may concern:

Be it known that I, JAMES A. SHARPNACK, a citizen of the United States, and a resident of Rices Landing, in the county of Greene 5 and State of Pennsylvania, have invented a new and Improved Facing Tool, of which the following is a full, clear, and exact description.

This invention relates to facing tools, and 10 has reference more particularly to a tool of this kind which comprises an elongated shank adapted to be introduced into the registering openings of the steering knuckle yoke of an axle, and a cutter removably carried by the shank, and extending laterally 15 beyond the same.

An object of the invention is to provide a simple and efficient facing tool particularly useful in facing steering knuckle yokes of 20 automobile axles, which can be inexpensively manufactured, and which requires no special experience or skill for its manipulation.

A further object of the invention is to provide a tool of the class described by means of 25 which smooth and even faces can be easily and rapidly formed, with which cutters of different kinds and sizes can be used, which can be employed for steering knuckle yokes of different kinds, and which may be employed for a variety of purposes.

References to be had to the accompanying drawings in which like reference numerals indicate corresponding parts in all the figures, and in which—

35 Figure 1 is an elevation of one end of an automobile axle, partly in vertical section, showing an embodiment of my invention applied thereto;

40 Figure 2 is an elevation of the upper end of the shank of one form of the tool;

Figure 3 is a group view showing a cutter in side elevation, end elevation, and in plan view;

45 Figure 4 is a fragmentary elevation of the tool showing a different form of cutter used therewith;

Figure 5 is a transverse section on the line 5—5 of Figure 4;

50 Figure 6 is a similar view on the line 6—6 of Figure 4; and

Figure 7 is a view similar to Figure 1, showing a modified application of the tool.

Before proceeding to a more detailed explanation of my invention, it is to be noted 55 that while the tool is particularly useful in facing steering knuckle yokes and bushings

of axles of automobiles, such as Ford automobiles, it can also be used for other purposes. Certain of the details of construction form no part of the invention, and may 60 be varied in accordance with individual preference or special conditions without departing from the spirit of the invention.

Referring more particularly to the drawings, I have shown part of an axle 10, having a steering knuckle yoke 11, terminating in an upper arm 12 and a lower arm 13. These arms have registering openings 14 and 15, which in the usual manner receive the steering knuckle pin or shaft, the steering knuckle 16 being received between the arms.

In one form of my invention, I provide a shank 17 having one end 18 threaded, and the other end 19 of reduced tapered form terminating in a squared head 20, adopted to receive a wrench or other suitable tool by means of which the shank can be turned to operate the tool. Below the threaded end, the shank has a transverse slot 21 of 80 rectangular cross-section. This slot is formed to receive an elongated cutter 22, having at opposite ends cutting edges 23. It is provided in its lower edge with a rectangular notch 24 which forms a pair of 85 spaced downwardly disposed extensions 25. Mounted upon the threaded end of the shank is a nut 26 below which is carried a helical spring 27 encompassing the shank.

When the tool is to be used, for example 90 in facing the inside of the yoke arm 12, it is positioned in the openings 14 and 15, as shown in Figure 1, with the spring engaging the upper side of the arm 12. The cutter is positioned in the slot 21 with the 95 extensions below the lower edge of the slot at each side of the shank, thus preventing lateral movement of the cutter. The nut 26 is turned down to place the spring under tension so that the shank is drawn upwardly, 100 and the cutting edges of the cutter are maintained in operative engagement with the surface to be faced. By turning the shank in any convenient manner, the facing action is rapidly and easily carried out.

To adapt the tool for another use, I apply it in a modified form. The shank below the slot 21 has an opening 28 drilled through it. In this opening is snugly fitted a pin 29, the ends which project beyond the sides of the shank. In this form of device I employ a cylindrical milling cut-

ter 30, the upper edge of which is provided with the usual cutter teeth 31. The cutter fits snugly but movably upon the shank, and has its lower edge provided with a pair 5 of recesses 32 at diametrically opposite points to receive the ends of the pin 29, to lock the cutter in position and cause it to turn with the shank.

This form of the tool can be used for 10 a variety of purposes, as shown for example in Figure 7. It can be employed to face the ends of steering knuckle bushings 33. For this purpose, the shank is placed within and passing through the steering 15 knuckle 16 with the cutter 30 engaging the end of the bushing to be faced. With this form of the device, the nut 26 holds the spring 27 against the opposite end of the steering knuckle as shown.

20 Having thus described my invention, I claim:—

1. A facing tool, comprising an elongated shank having one end threaded and adapted to be inserted in the registering openings 25 of a steering knuckle axle and turned therein, a removable cutter on the shank intermediate of its ends, the cutter being provided with a recessed lower edge and the shank with means for engaging the recessed

edge of the cutter, a nut on the threaded end 30 of the shank, and a spring on the shank and adapted to be compressed by the nut between it and the said axle, whereby the cutter will be held in locked engagement with the inner face of one arm of the knuckle 35 axle.

2. A facing tool comprising a shank having one end screw threaded and its other end adapted to receive a tool for turning it, a cutter on the shank intermediate of its ends, 40 a nut on the threaded end of the shank, and a spring on the shank and adapted to be compressed by the nut between it and the work to hold the cutter in engagement with the work.

3. A facing tool comprising an elongated shank having one end threaded and its other end reduced and terminating in a polygonal portion, a cutter removably mounted on the shank and having interlocking engagement 50 therewith, a nut on the threaded end of the shank, and a spring on the shank and adapted to be compressed by the nut between it and the work, whereby the cutter will be held in interlocked engagement with the 55 shank and in engagement with the work.

JAMES ANSON SHARPNACK.
